LITTER BAG

David W. Walker, 2113 State St.,
New Albany, Ind. 47150

Filed Jan. 10, 1973, Ser. No. 322,451

Term of patent 14 years

Int. Cl. D7—07

U.S. Cl. D7—193

FIG. 1 is a front elevational view of a litter bag, showing my new design;

FIG. 2 is a side elevational view thereof;

FIG. 3 is a rear elevational thereof; and

FIG. 4 is a top plan view thereof.

I claim:

The ornamental design for a litter bag, as shown.
